UNITED STATES PATENT OFFICE

2,586,457

STRETCHABLE BELT

Max Epstein, Rochester, N. Y., assignor to Hickok Manufacturing Company, Inc., Rochester, N. Y., a corporation of New York

Application August 10, 1949, Serial No. 109,580

9 Claims. (Cl. 2—322)

1

This invention relates to stretchable belts for personal wear.

One object of the invention is to provide a belt for personal wear embodying, among other characteristics, a belt particularly constructed to flex or stretch in conformity with body movements of the wearer and otherwise provide for the wearer's comfort in the wearing of the belt.

Another object of the invention resides in the provision of a stretchable belt, embodying economy and inexpensiveness of manufacture and in which the stretchable means is concealed within the belt and the amount of stretch of the stretchable means is limited to prevent over-stretching and consequent unnecessary wear on the stretching means.

A still further object of the invention is to provide a new ornamental and attractive design of belt for personal wear embodying stretchable means on opposite sides of the buckle fastening means operable to stretch to accommodate any normal or abnormal movements of the body at the waist line obviating any unnecessary tightening of the belt on the wearer.

With the above and other objects in view, the invention consists in the construction and novel combination and arrangement of parts herein-after fully described, illustrated in the accompanying drawings and pointed out in the claims hereto appended, it being understood that various changes in the form, proportions, and minor details of construction, with the scope of the claims, may be resorted to without departing from the spirit of sacrificing any of the advantages of the invention.

In the accompanying drawings:

Figure 1 is a perspective view of the invention, showing one form of the belt in unbuckled condition;

Figure 2 is a fragmentary slightly enlarged front view of the belt, having the ends thereof buckled together;

Figure 3 is a front elevation of the buckle end member of the belt;

Figure 4 is a similar view, parts being broken away;

Figure 5 is a longitudinal sectional view on the line 5—5 of Figure 2;

Figure 6 is an enlarged fragmentary view of one end of the belt body extending through openings at the outer end of either of the end members of the belt;

Figure 7 is a transverse sectional view on the line 7—7 of Figure 1;

Figure 8 is a transverse sectional view on the line 8—8 of Figure 2;

2

Figure 9 is a fragmentary view showing a modified form of overlapping connection of the ends of the strands 13 and 14 with the elastic webbing 45 secured in the overlapping relation by stitching;

Figure 10 is a perspective view of a modified form of unbuckled belt, parts being broken away to show the connection of an end of a solid belt connected positively to the stretchable member carried by each end member of the belt.

Figures 11 to 14, inclusive, illustrate fragmentary views of a modified form of the invention; Figures 15 to 20, inclusive, illustrate fragmentary views of a still further modification of the invention.

Referring now to the accompanying drawings, and first more particularly to Figures 1 to 9, inclusive, illustrating one embodiment of the invention, the reference character 10 indicates, generally, the body portion of a belt for personal wear, the characters 11 and 12 indicating end members, constituting a buckle end member and a free end member, respectively.

The belt body 10, in this form of the invention, 25 is composed preferably of narrow, flat, spaced, substantially rectangular shaped strands 13 and 14 of leather or other suitable material.

The strands 13 and 14 are maintained in substantially uniform spaced relation throughout 30 their lengths by a plurality of spaced, similarly formed spacing members 15, 16 and 17 slidable on the strands 13 and 14 and located between the ends of the strands, as shown. Any desired number of these spacing members may be employed in the make-up of this particular open work belt body and they may be composed of any suitable material, preferably leather, and, if desired, they may be of a color contrasting with the color of the strands 13 and 14.

40 The material of which the spacing members 15, 16 and 17 are formed is in each instance folded to provide each with an intermediate body portion 18 and open ended sleeve portions 19 and 20 at the ends of the respective body portion 18 to snugly but slidably receive the respective strands 13 and 14, whereby the said spacing members are adjustably supported in different positions on the strands. The folded portions of said body portions 18 of the spacing members are stitched together along lines 21 and 22 adjacent the inner edges of the spaced respective strands to complete the formation of said sleeves 19 and 20 and to connect the overlapped ends of the folded material together.

55 The opposite ends of the strands 13 and 14 of the open-work body portion of the belt are free

and extend beyond the outermost spacing members for a purpose presently understood.

The free ends of the strands 13 and 14 may be connected in any suitable manner to buckle fastening members, but in this embodiment of the invention, new types of buckle fastening end members 11 and 12, hereinbefore denoted, are employed. For instance, there is the buckle end member 11 and the free or tongue end member 12. The buckle end member 11 is formed of a single piece of leather or other suitable material 23, broadened in width or spatulate in shape at the inner end thereof, as at 24, the outer narrower portion 23 being folded back upon itself and stitched longitudinally along its side edges to the inner face of the body of the material at the inner end thereof, as at 25 and 26, to provide a loop 27 to pivotally receive the rear bar 28 of a suitable buckle frame 29 carrying a buckle tongue 30. The inner end of the buckle tongue 30 is pivoted on said rear bar 28 of the buckle frame in the usual manner and extends therefrom through an aperture 31 in the loop 27. This backwardly turned portion forming said loop 27 is further secured to the body of the end member 11 by spaced transverse stitches 32, 33 and 34, the stitchings 33 and 34 being on opposite sides of the usual belt guide loop 35 which is stapled or otherwise secured to the buckle end member, as at 36, before the formation of said loop 27.

The outer end of the material of which the end member 11 is formed is folded back upon itself, providing a wall 37, and stitched or otherwise secured along its longitudinal edges as at 38 and 39 and at its inner end, as at 40, for cooperation with the body of the material of which the end member is composed, to provide a pocket 41.

The pocket 41 is notched at opposite sides to provide spaced openings 42 and 43 at its outer end, with a portion intermediate said openings constituting an abutment 44 for a purpose presently explained.

A relatively short or small piece of elastic webbing 45 is located and concealed within said pocket 41 of the ornamental buckle end member 11 and has its inner end fixedly secured in the pocket by the aforesaid stitches 40 by which the inner end of the wall 37 is secured to the inner face of the body of the said buckle end member 11 to form the said pocket 41.

The elastic webbing 45 has its outermost end secured to the respective ends of the strands 13 and 14, in abutting alining relation therewith, by means of staples or stitching 46 or in any other suitable manner. This manner of connecting the respective inner ends of the strands 13 and 14 to the elastic webbing 45 provides clearance for the engagement of the outer edge of the webbing between said pocket openings 42 and 43 to engage the aforesaid abutment 44 to limit the amount of outward expanding stretch of the elastic webbing, thereby not only enhancing the life of the webbing, but also providing for a noiseless stop contact between the webbing and abutment as distinguished from contacting metal surfaces for limiting or stop purposes. The elastic webbing constitutes a combined stretchable member and stop means to limit outward movement of the end member 11.

The free or tongue end 12 of the belt has an enlarged or spatulate or ornamental inner end 47 and a narrower outer end 48 for insertion into and withdrawal from the buckle frame 29 in the usual manner and it also has spaced perfora-

tions 49 for interchangeable or adjustable connection with the buckle tongue 30.

The inner end of the free or tongue end member 12 is formed exactly the same as the inner end of the buckle end member 11, including a pocket 49' formed in the same manner as the pocket 41 and like the latter including spaced openings 50 and 51 and abutment 52 and extendible or elastic webbing element 53 connected at one end in the pocket and connected to the respective ends of the strands 13 and 14 in the identical manner as hereinbefore described in connection with the pocket 41 of the buckle end member 11 and further detailed description of the end member 12 would seem unnecessary except perhaps to add that the outer narrower end 48 conforms substantially in width to the width of the outer end of the buckle end 11 and the width of the body of the belt and has a series of spaced perforations 49 for coaction with the buckle tongue 30 to fasten the ends of the belt together.

In Figure 10 another embodiment of the invention is illustrated, showing the intermediate body portion 57 of the belt in solid form and having its opposite ends bifurcated or slotted to provide spaced elements 58 and 59, the extremities of which abut the respective ends of the elastic webbing 60 and secured in the abutting relation by suitable fastenings 61, such as stitching; otherwise the structure of this embodiment of the invention is the same as the embodiment first described herein. It is to be understood that in both forms of the invention the ends of the intermediate body portion of the belt may be secured to respective elastic webbings in any other manner than as shown, as for instance, in Figure 9, where the ends of the strands overlap the elastic webbing and stitched, as at 62.

In both forms of the invention, there is provided a belt for personal wear of an attractive, ornamental design incident to the enlargements or spatulate shaped portions of the end members of the belt and arranged on both sides of the buckle fastening means. Either or both of the stretchable elements may function according to the needs or comfort of the wearer and, of course, any suitable type of buckle, other than that illustrated, may be employed.

A modification of the invention is illustrated in Figs. 11 to 14 inclusive wherein the solid strap 63 has like expandible and contractible end members, the tongue end members 64 being sufficient to illustrate the invention because of the sameness of structural characteristics of both of the end members. The strap 63, near each end, has a closed slot 65, the inner end of each of which slots is adapted to abut the abutment 66 to limit the expanding outward stretch of the respective elastic webbing 68, as in the previous forms illustrated and described.

To assemble the parts, in this form of the invention, to enclose the elastic webbing 68 in the respective pocket, as previously described in other forms of the invention, the tongue end member 64, for instance, is threaded through the respective slot 65 of the strap body portion 63, as shown in Fig. 12, to bring the reduced portion 69, which forms the abutment of the character previously described, into the respective slot 65. This action necessitates a slight curling of the edges of the inner spatulate shaped wall portion of the tongue end member, as shown in Fig. 12, together with a slight twisting of the portion 69, as also shown in Fig. 12. After said reduced por-

tion 69 is brought into the aforesaid slot 65, the spatulate shaped pocket wall 70 of the tongue end member is turned, as shown in Fig. 11, and brought into parallelism with the spatulate shaped pocket wall 71. The walls 70 and 71 are finally sewed or stitched together about the edges thereof to form the respective pocket for the respective elastic webbing 68 which is secured at the respective end of the strap by stitching 73 or otherwise. The opposite end of the elastic webbing is secured to the inner face of the wall 71 by stitching 74 or otherwise. The walls 70 and 71 of the pocket are secured by stitching 75 or otherwise. This invention functions the same as the previous forms described, the outer closed ends of the slots in the form shown in Figs. 11 to 14 inclusive limiting the inward movements of the retractile elastic webbings and with the opposite closed end of the slot limiting the outward stretch of the elastic webbing.

Another embodiment of the invention is illustrated in Figs. 15 to 20, inclusive, wherein both end members are alike but only one shown, it being sufficient for purposes of illustration of this modified form of the invention. In this form of invention now being described, the tongue end 76 has a spatulate wall 77, having side flaps 78 and 79 adapted to be stitched together at their opposing edges as at 80 and the flaps constituting a wall for cooperation with the wall 77 to provide a pocket of the character previously described.

As in the form of invention illustrated in Figs. 11 to 14 inclusive, this latest form of the invention includes a solid strap 81 having a closed slot 82 near each end and the elastic webbing 83 is secured at one end by stitching 84 or otherwise to one end of the strap 81 with its opposite end secured by stitching 85 to the inner face of wall 77.

The wall 77 has a relatively long strip 86 extending from its rear edge, between the edges thereof, and which strip extends inwardly through said slot 82 of the strap and into the pocket and, at its outer end, secured by stitching 85 which secures the inner ends of the aforesaid flaps 78 and 79 to the inner end of the pocket wall 77 and which stitching also secures the free end of said strip 86 in said pocket. In this last form described, the abutment is shown at 88, and of a curved formation as in the forms previously described, and which is that portion of the aforesaid strip 86 and which cooperates with the closed ends of the respective slot 82 as in the forms previously described.

In each form of the invention, the free or tongue end member is in the nature of a combined tongue and pocket, the pocket being at the inner end of the tongue and carried thereby. The pocket opens outwardly and slidably receives the respective end of the body of the strap. There is an expansible and contractible element in the pocket which is fixed at one portion of the pocket and at another portion fixed to the body of the strap.

What is claimed is:

1. A stretchable belt including a main body part and an end member, the latter having a pocket extending to its inner end and slidably receiving therein an end portion of the main body part, said pocket at its outer end intermediate the sides thereof having a transversely extending end wall portion connected with opposite side walls of the pocket, said end of the pocket being open at each side of said intermediate end wall por-

tion, said end portion of the main body part having laterally spaced opposite parallel longitudinally extending wall portions, said laterally spaced wall portions straddling said end wall portion of the pocket and extending through the openings at either side of said end wall portion into the pocket, and an elastic member completely enclosed within said pocket secured at one end to the inner end portion of the pocket and secured at its opposite end to said end portion of the body part within the pocket, said end wall portion serving as means for limiting the extent of stretch of said elastic element.

2. A stretchable belt of the construction defined in claim 1 and in which the elastic element consists of a strip of elastic webbing.

3. A stretchable belt of the construction defined in claim 2 and in which the belt has an end member of the construction set forth in claim 2 at each end thereof, and the end members have on their outer end portions cooperating buckle fastening means to connect the same together.

4. A stretchable belt including a main body part and an end member, the body part comprising a pair of laterally spaced strands, means engaging the strands and maintaining the same in substantially uniform spaced relation, the end member having a pocket extending from its inner end portion slidably receiving an end portion of the main body part, said pocket at its outer end intermediate the sides thereof having a transversely extending end wall portion connected with opposite side walls of the pocket, said end of the pocket being open at each side of said intermediate end wall portion, the strands at said end portion of the main body part straddling said end wall portion of the pocket and extending through the openings at either side of said end wall portion into the pocket, and a strip of elastic webbing within said pocket secured at one end to the inner end portion of the pocket and secured at its opposite end to the strands of said end portion of the body part within the pocket, said end wall portion serving as means for limiting the extent of stretch of said elastic element.

5. A stretchable belt as defined in claim 4 and in which the means for maintaining the strands of the body part in substantially uniform spaced relation consists of a plurality of sleeve members located at intervals intermediate the ends of the body part and longitudinally adjustable thereon.

6. A stretchable belt including a main body part having a closed longitudinally extending slot in an end portion thereof and an end member having a pocket extending to its inner end, said pocket at its outer end intermediate the sides thereof having a transversely extending end wall portion connected with opposite side walls of the pocket, said end of the pocket being open at each side of said intermediate end wall portion, said end wall portion slidably engaging the slot in said end portion of the body part, and a strip of elastic webbing completely enclosed within said pocket secured at one end to the inner end portion of the pocket and secured at its opposite end to said end portion of the body part within the pocket, said end wall portion serving as means for limiting the extent of stretch of said elastic element.

7. A stretchable belt including a main body part and an end member, the latter having a pocket extending to its inner end and slidably receiving therein an end portion of the main body part, said pocket having a relatively long strip integral

with and extending from one side wall of the pocket at the outer end thereof across said end of the pocket to the opposite side wall thereof and thence longitudinally within the pocket along said last mentioned side wall and being secured thereto, said end portion of the main body part having laterally spaced opposite parallel longitudinally extending wall portions, said laterally spaced wall portions straddling said end wall portion of the pocket and extending through the openings at either side of said end wall portion of the pocket into the pocket, and an elastic member completely enclosed within said pocket secured at one end to the inner end portion of the pocket and secured at its opposite end to said end portion of the body part within the pocket, said end wall portion serving as means for limiting the extent of stretch of said elastic element.

8. A stretchable belt including a main body part and an end member, the latter having an inner section provided intermediate its ends with notches in opposite side marginal portions thereof, said inner section being folded back upon itself at said notches and secured along its marginal portion to the opposing fold to provide a pocket having at its outer end intermediate its side marginal portions a transversely extending end wall with an opening at each side of said end wall, the outer end portion of the main body part having laterally spaced parallel longitudinally extending wall portions straddling said end wall portion of the pocket and extending through the openings at either side of said end wall portion into the pocket, and an elastic member completely enclosed within the pocket secured at one end to the inner end portion of the pocket and secured at its opposite end to said end portion of the body part within the pocket, said end

10 wall portion serving as means for limiting the extent of stretch of said elastic member.

9. A stretchable belt including a main body part having a closed longitudinally extending slot in an end portion thereof, and an end member having an inner section provided intermediate its ends with notches in opposite side marginal portions thereof, the inner section extending through the slot in the end portion of the body part and being folded back upon itself at the notches in its side marginal portions and secured along its marginal portions to the opposing fold to provide a pocket having at its inner end an end wall intermediate its side marginal portions with an opening at each side of said end wall, said pocket slidably receiving therein said end portion of said body part, said end wall of the pocket slidably engaging the slot in the end wall of the body part, and an elastic member completely enclosed within said pocket secured at one end to the inner end of the pocket and secured at its opposite end to said end portion of the body part within the pocket, the end wall portion serving as means for limiting the extent of stretch of said elastic element.
